UNITED STATES PATENT OFFICE.

CASMER F. WOZNICKI, OF SOUTH BEND, INDIANA.

FEEDING ATTACHMENT FOR PRINTING-PRESSES.

1,372,583.

Specification of Letters Patent. Patented Mar. 22, 1921.

Application filed July 9, 1920. Serial No. 394,947.

To all whom it may concern:

Be it known that I, CASMER F. WOZNICKI, a citizen of the United States of America, residing at South Bend, in the county of 5 St. Joseph and State of Indiana, have invented new and useful Improvements in Feeding Attachments for Printing-Presses, of which the following is a specification.

The object of the invention is to provide 0 a paper positioning and holding means for use as an attachment in connection with the feed mechanisms of printing presses of the Miller and analogous types wherein the movement of the blank sheets from the feed boxes to, and the positioning of the same upon, the platen or tympan is accomplished 15 through the agency of gripper mechanism including grippers for engaging the forward edge of a sheet located and positioned with reference thereto by means of paper 20 separating devices and advancing the sheet in a path traversing the platen and releasing the same adjacent to and in approximately proper relation with paper gages carried by the platen; and more especially to 25 provide, for use in connection or coöperation with the grippers, a means serving to direct and hold the forward edge and front corners of the paper sheet for engagement by spring or yielding paper clips designed to 30 receive the edges of the sheet, to guard against the possibility of such edges passing over the clips instead of between the same and the plane of the platen, and also to compensate for the necessary elevation of the 35 forward edge of the sheet above the paper receiving surface of the platen by reason of the thickness of the lower jaw of the gripper, and prevent the rebounding of a sheet when released by the grippers, due to the impact 40 of the edge of the sheet against the end gages and the tendency of the sheet upon contacting with the gages to spring back or move in the opposite direction to that in 45 which it has been carried by the gripper mechanism and thus remove its forward edge from proper contact and alinement with the end gages; and with these objects in view the invention consists in the 50 construction and combination of parts, illustrated for convenience in connection with a paper feeding mechanism of the type employed in the job printing presses commercially recognized as the Miller type and constituting a preferred embodiment thereof, it being understood, however, that changes

in form, preparation and details may be resorted to within the scope of the appended claims without departing from the principles involved.

60 In the drawing:

Figure 1 is a side view of a portion of a printing press structure showing a feed attachment constructed in accordance with the invention applied in the operative position 65 thereto.

Fig. 2 is a plan view of the platen and related parts of the press showing the position of the feeding mechanism at an intermediate point in the path of its movement. 70

Fig. 3 is a detail view in perspective of the attachment applied in the operative position to a gripper carrying bar adjacent to a gripper to show the coöoperative action 75 thereof.

Fig. 4 is a detail sectional view taken in the plane of a gripper and through the adjacent portion of the platen to indicate the position of the forward edge of the paper sheet as carried thereby.

Fig. 5 is a similar sectional view taken in the plane of the attachment to show the manner in which the adjacent portion of the forward edge of the sheet is positioned thereby in contact with the upper surface 80 of the platen.

Fig. 6 is a detail transverse section showing the forward edge of the paper sheet and the position of the same as determined by the gripper and the attachment with relation 90 to the clip for holding the side edge of the sheet when positioned upon the platen.

Fig. 7 is a detail bottom plan view of the bearing member of the presser foot.

Fig. 8 is a detail in perspective of the 95 positioning fork.

Fig. 9 is an enlarged sectional view of the shank holding head.

In order that the necessity for and utility 100 of a device embodying the invention may be recognized in connection with the paper feeding mechanism of a printing press of the type indicated, the attachment designated generally as 10 is shown in connection with a printing press having a bed 11 above 105 which is located the inking plate or disk 12 traversed by the inking rollers 13, a platen or tympan 14 connected with the frame of the machine by link 15 and movable toward and from the bed upon which are located 110 the type chases, the feed box 16 in which the stock of paper is arranged preparatory

for printing, the delivery box 17 in which the printed sheets are deposited by the delivery mechanism represented by the fork 18 having the delivery grippers 19, a sheet separating mechanism represented in the drawing by a suction member 20 movable toward and from the plane of the top-most sheet in the feed box for successively elevating the forward edges of the sheets into position for engagement by the grippers of the feed mechanism, and a paper feeding device having the gripper carrying bar 21 supported by racks 22 and having mounted thereon the grippers 23 of which the movable and fixed jaws 24 and 25 are adapted as in the ordinary practice for separation to receive the front edges of the separated sheets as they are successively presented by the action of the separating mechanism at the limit of the return movement of the paper feeding mechanism in the direction indicated by the arrow in Fig. 1. In connection with the gripper carrying bar and grippers of which any suitable or preferred number may be carried by said bar, according to the character of the work, the width of the sheets to be fed, and the like, there is employed the usual gripper actuating bar or element 26, movable by mechanism well known in the art, and therefore not specifically illustrated herein, for alternately opening and closing the gripper jaws to respectively engage a sheet at the feed box and release the same when it has been positioned upon the platen.

It will be noted, particularly by reference to Figs. 4 and 6, that the engagement of the forward edge of the paper sheet shown at 27 by the jaws of the gripper, spaces the said forward edge slightly above the plane of the surface of the platen 14, and although in mechanisms of this type it is usual to so regulate the operation of the grippers as to release the sheet under such conditions and in such relation to the end gage blocks 28 of the platen as to cause the edge of the sheet to bear uniformly against and lie in alignment with said gages, for lateral adjustment to and contact with the side gages 29 of the platen by the lateral positioning fork 30, commonly employed in this connection and illustrated in Fig. 2, there are conditions encountered in job printing work which defeat the purpose of such devices and arrangements as have heretofore been adapted in this connection, and which result in an improper positioning of the sheet upon the platen and hence the improper application of the type impressed upon the surface thereof and consequently loss of time and material in the operation of the press. For example, the sheets may be slightly curled or warped, or the impact of the forward edge of the sheet against the end gages or stops 28 may cause a buckling

of the sheet with the resultant rebound withdrawing the forward edge from contact with the stops to such a degree as not to be rectified by the operation of the positioning fork. Moreover it is desirable in order to insure the accuracy of the work of the press to provide means such as edge clips 31 and 32, located respectively at the side and end edges of the sheet, and carried by the platen, and consisting of spring fingers or the equivalents thereof as indicated for example in Fig. 6, beneath which the edges of the sheet or between which and the upper surface of the platen the said edges of the sheet may be inserted to insure the retention of the sheet in proper relation with the side and end gages after the release of the sheet by the gripper and the necessary movement thereof by the positioning fork, and notwithstanding the fact that the press mechanism embodies the usual swinging gripper fingers 33 for movement into engagement with the sheet after it has been positioned and before the platen moves into operative relation with the bed.

Owing to the fact that the engagement of the grippers with the forward edge of the sheet in feeding the latter to its position on the platen necessitates the arrangement of the lower jaw 25 of each gripper beneath the sheet, and therefore between the forward edge of said sheet and the upper side of the platen, it is obvious as will be seen for example by reference to Fig. 6 of the drawing, that there is a tendency to hold the sheet in such a position that the forward and side edges thereof adjacent to the corner will not pass under the clips 31 and 32 or either of them, and as a result, in the event that there should be a slight transverse curl in the sheet, the lateral action of the positioning fork will tend to push the side edge of the sheet over the side gage 21 and thus wholly disarrange the same with reference to the platen with the result that the printed matter is not properly positioned upon the sheet.

To overcome these disadvantages and insure the proper positioning of the sheet upon the platen regardless of any distortion in the form thereof, and to insure the engagement of the end and side edges of the sheet with the holding clips 31 and 32, there is employed a vertically yieldable presser foot 33, forming a part of the attachment 10 and having an upwardly and rearwardly deflected lower bearing member 34 beneath which the forward edge of the sheet is disposed as the grippers carried by the bar 21 move into engagement with the sheet supported for that purpose by the suction element 20 of the separating mechanism, and as the sheet is drawn forward over the surface of the platen by the action of the grippers it is depressed outside of the zone of operation of the grip.

pers and adjacent to the side edges thereof as indicated in Figs. 3, 5 and 6, so that the terminals of the end edge and the forward portions of the side edges of the sheet are held 5 firmly in contact with the surface of the platen, and thus must pass under the holding clips 31 and 32 before the sheet is released by the grippers. Said pressure foot is carried by the lower end of a shank 35 10 of angular or irregular cross-section as shown slidably fitted in a guide 36 attachable by means of a clamp 37 to the gripper carrying bar 21 and locked for example by a thumb screw 38, said shank being fitted 15 at its upper end with a head 39 engaged with the gripper actuating bar 26 and therefore adapted to be raised by the said actuating bar after complete release of the sheet to insure the backward or return movement 20 of the presser foot out of contact with the sheet and therefore without tending to disturb the same after it has been positioned upon the platen. The head 39 is preferably provided with a shouldered recess 40 25 providing a stepped bearing for the edge of the actuating bar 26 so that when the gripper carrying bar reaches the limit of its paper positioning movement, and the actuating bar 26 tilts to raise the movable jaw 24 of 30 the gripper to release the forward edge of the sheet, said actuating bar will have lost motion with relation to the retaining member 10 embodying said presser foot 33, and thus leave the presser foot in contact with 35 the edge of the paper sheet after the release of the latter by the grippers. The presser foot in other words will be permitted by gravity to drag upon the surface of the sheet for a short distance as the grippers 40 continue their advance movement to clear 45 the sheet and thus will counteract any tendency of the sheet to rebound and will insure the retention of the forward edge of the sheet in engagement with the end clip 32 and 50 in contact with the end gages 28 to avoid any rearward floating of the sheets due to air which may be between the sheet and the surface of the platen. The retaining member thus acts to permit the settling of the forward edge of the sheet upon the surface 55 of the platen after the disengagement of the grippers therefrom and during the withdrawal of the lower jaws of the grippers from their positions and between the sheet and the surface of the platen. Obviously the continued movement of the actuating bar 26 in the elevation of the grippers so as to permit of the return movement of the latter without coming in contact with and disturbing 60 the sheet will also raise the retaining member to an extent sufficient to pass over the sheet and permit of the return of the feeding mechanism to the initial position for engagement with the succeeding sheet 65 at the feed box, such succeeding sheets hav-

ing in the meantime been positioned by the sheet separating mechanism for engagement by the grippers.

It will be noted that the retaining device is designed to be applied as an attachment to the standard elements of a commercial type of printing press without necessitating any alterations in the construction or arrangement of such elements, as a means of supplementing the operation of the grippers in the 70 positioning of the sheets and as a means of overcoming the insufficiencies of the grippers as now employed to insure a uniform positioning of the sheets upon the platen to the end that the inconvenience and losses incidental to the operation of such elements may be avoided, and in order that the operation of the retaining member may be regulated to suit the thickness of the sheets which are being handled, the head 39 thereof is adjustably connected with the stem or shank 35, as by threading the same thereon as indicated at 31, so that for example when tissue paper is being positioned by mechanism, the presser foot may be relatively 85 lowered to insure the contact thereof with the sheet until after a relatively greater movement of the actuating bar 26 has occurred, the bearing of the presser foot upon the sheet being due to gravity incidental to 90 the weight of the retaining member including the presser foot, shank, and head, supplemented primarily by the actuating bar 26 but independently thereof when the movement of said actuating bar to open the gripper takes place, so that the downward pressure of the foot 34 is gradually reduced as the same advances and prior to the complete removal of the foot from contact with the sheet. 100

Having described the invention, what I claim as new and useful is:

1. A sheet retaining member for the feed mechanism of printing presses having a gravity actuated presser foot for holding 110 the forward edge of the sheet in contact with the surface of the platen during its approach to the end gages and means whereby the pressure of said foot is gradually reduced prior to disengagement from the sheet. 115

2. A sheet retaining device for the feed mechanism of printing presses having a presser foot for contact with the upper surface of the sheet, a shank carrying the presser foot, and a guide for the shank provided with a clamp for detachable engagement with a gripper carrying bar, said shank being provided with a head for engagement by the gripper actuating element. 120

3. A sheet retaining device for the feed mechanism of printing presses having a presser foot for contact with the upper surface of the sheet, a shank carrying the presser foot, and a guide for the shank provided with a clamp for detachable engage- 125

- ment with a gripper carrying bar, said shank being provided with a head for engagement by the gripper actuating element and adjustable to vary the relation of the bearing surface of the presser foot therewith.
4. A sheet retaining device for the feed mechanism of printing presses having a presser foot for contact with the upper surface of the sheet, a shank carrying the presser foot, and a guide for the shank provided with a clamp for detachable engagement with a gripper carrying bar, said shank being provided with a head for engagement by the gripper actuating element and having a stepped seat for engagement by said gripper actuating bar.
5. The combination with the gripper of a printing press feed mechanism, of a retainer having a yielding presser foot movable in a path parallel with the gripper and bearing upon the upper surface of the sheet engaged by the gripper for retaining said sheet in contact with the surface of the platen.
- 20 6. The combination with the paper sheet gripper of a printing press feed mechanism, of a retaining member arranged adjacent to and movable in a path parallel with the gripper and having a presser foot yieldingly impelled toward the plane of the platen and provided with an upwardly deflected rear end.
- 25 7. The combination with the paper sheet

gripper of a printing press feed mechanism, of a retaining member arranged adjacent to and movable in a path parallel with the gripper and having a presser foot yieldingly impelled toward the plane of the platen and a bearing member extending in rear of a transverse line through the paper 40 engaging members of the gripper.

8. The combination with the paper sheet gripper of a printing press feed mechanism, of a retaining member arranged adjacent to and movable in a path parallel with the gripper and having a presser foot yieldingly impelled toward the plane of the platen and a bearing member extending in rear of a transverse line through the paper 45 engaging members of the gripper and provided with a corrugated paper contacting surface.

9. The combination with the paper engaging gripper of a printing press feed mechanism of sheet engaging clips carried by the platen, and a retaining member movable in a path parallel with the gripper and between the same and said paper engaging clips and having a presser foot yieldingly impelled toward the plane of the platen for 60 holding the edge of the sheet in contact with the surface thereof.

In testimony whereof I affix my signature.

CASMER F. WOZNICKI.
